(57) **CLAIM**

The ornamental design for an electric scooter, as shown and described.

DESCRIPTION

FIG. 1 is a perspective view of an electric scooter according to the present invention;

FIG. 2 is a front view of the electric scooter of FIG. 1;
FIG. 3 is a rear view of the electric scooter of FIG. 1;
FIG. 4 is a left side view of the electric scooter of FIG. 1;
FIG. 5 is a right side view of the electric scooter of FIG. 1;
FIG. 6 is top plan view of the electric scooter of FIG. 1; and,
FIG. 7 is a bottom plan view of the electric scooter of FIG. 1.

The broken lines represent boundaries of the claimed design. The areas shown in half-tone de-emphasized shading illustrate portions of the article that from no part of the claimed design. Neither the broken lines themselves nor the lightened areas form any part of the claimed design.
